VENTILATED BLOCK AND WALL CONSTRUCTION

Filed Feb. 2, 1938

FIG. 7.

FIG. 2

FIG. 3

FIG. 4

A technical line drawing of a mechanical assembly, likely a component of a printing press. The drawing shows a base structure with various numbered parts: 11, 12, 13, 14, 15, 16, 17, 18, 19, 20, 21, 22, and 23. A central vertical element is labeled 20, 20. The drawing is signed 'Stanley' in the bottom right corner.

VENTILATED BLOCK AND WALL
CONSTRUCTION

Stanley Brozek, Dearborn, Mich.

Application February 2, 1938, Serial No. 188,375

7 Claims. (Cl. 72—102)

My invention relates to a building block and a wall made therefrom.

An important object of the invention is to provide a block of the above mentioned character, so constructed that the wall made therefrom will have proper interior ventilation, to prevent cracking or the like and which will be strong.

A further object of the invention is to provide a block of the above mentioned character which 10 may be conveniently manually manipulated when laying.

Other objects and advantages of the invention will be apparent during the course of the following description.

15 The invention shown in the present application is related to the invention shown in my co-pending application, Serial No. 91,199, filed July 17, 1936, and which matured into Patent No. 2,114,774, under date of April 19, 1938.

20 In the accompanying drawing forming a part of this application and in which like numerals are employed to designate like parts throughout the same,

Figure 1 is a plan view of a wall embodying 25 my invention;

Figure 2 is a similar view showing the next upper layer;

Figure 3 is a side elevation of the wall, parts in central vertical longitudinal section,

30 Figure 4 is a transverse section taken on line 4—4 of Figure 3, the keys omitted;

Figure 5 is a perspective view of the block, and;

Figure 6 is transverse section through one of 35 the blocks combined with a brick facing.

In the drawing, wherein for the purpose of illustration is shown a preferred embodiment of my invention, the numeral 10 designates the block as a whole. This block is L-shaped in cross-section and has a main recess 11 formed in one longitudinal corner thereof. This main recess extends through the entire length of the block. The block comprises a vertical side face 12 and a vertical side face 13, which are parallel. The 40 block comprises an extension 14 which projects above the horizontal wall 15. The block is provided in its opposite vertical ends with vertical locking recesses 16, extending through the top and bottom thereof and leading into the main recess 11. The block 10, Figure 5, is provided in its bottom with an air circulating recess or groove 17, preferably extending for the width of the end locking recesses 16 and in communication with the end locking recesses. The vertical 45 extension 14 is provided with an intermediate

locking recess 18, having a length twice that of the length of the end locking recesses. The recesses 18 have bottom walls 19. The numeral 20 designates vertical vent openings, having a vertical web 20' between them. The numeral 21 designates a longitudinal air circulating recess or groove, arranged opposite the groove 17. The groove 21 leads into the recesses 16. The opposite ends of the vertical vent openings 20 lead into the vent recesses or grooves 17 and 21. The 50 vent openings 20 project longitudinally beyond the intermediate locking recess 18, as shown. The grooves 17 and 21 produce intermediate portions 22 of suitable size to be held between the finger and thumb, in manipulation of the blocks. The 55 recesses 21 being open at the top, the portions 22 may be readily grasped.

The blocks are arranged in horizontal layers, in end to end relation, and the assembled locking recesses 16 produce locking passages which are 20 in alignment with locking passages produced by the recesses 18 of the blocks in the next upper horizontal layer, which blocks are inverted. The locking keys 23 are inserted in these recesses. The vertical vent passages 20 extending longitudinally beyond the recesses 18, afford free 25 communication between the several horizontal vent passages. These horizontal vent passages are produced by the vent grooves 17 and 21 and the spaced extensions 14, when assembled in 30 opposed relation.

While I prefer to use the locking keys 23, which may be solid, yet they may be dispensed with, if desired.

I have provided a block which is strong and 35 possesses the advantages of a solid block, but which has ample passages for ventilation.

In Figure 6, a block is shown, for building a wall with a brick facing. The blocks, in this wall, in the successive horizontal layers are not 40 inverted. Two layers of bricks 24 extending longitudinally are arranged at the face 12, while the third layer is arranged transversely and projects into the main recess 11. The blocks in the next upper horizontal layer will be laid upon 45 the upper flat face of the wall thus produced, and the longitudinal air vent or passage 17 will provide the desired circulation. The longitudinal passage 21 beneath the layer of transverse bricks also provides the desired circulation. Both 50 passages 17 and 21 extend throughout the entire length of the brick.

In view of the foregoing description, it is obvious that I have provided a block which will permit of a proper ventilation, by virtue of the lon- 55

gitudinal ventilating groove or recess 17 at the bottom and the longitudinal groove or recess 21. These grooves 17 and 21 provide ventilation throughout the entire length of the blocks. The 5 web 20 strengthens the block and permits of forming the vertical vent openings or passages suitably long to project beyond the recess 18, without sacrificing the desired strength of the block. The ventilation is throughout the wall 10 and also through the corners.

It is to be understood that the forms of my invention herewith shown and described are to be taken as preferred examples of the same and that various changes in the shape, size and arrangement of parts, may be resorted to, without departing from the spirit of my invention or the 15 scope of the subjoined claims.

Having thus described my invention, what I claim is:

- 20 1. A building block having a main recess at one longitudinal corner for providing a vertical longitudinal extension, said block being provided at its ends with locking recesses extending through the top and bottom thereof, said block being 25 provided upon one horizontal face with a longitudinal vent recess, said block being provided in its vertical extension with an intermediate locking recess and said block having a vertical vent passage in communication with the longitudinal 30 vent passage, the vertical vent passage extending longitudinally of the block beyond the end of the intermediate locking recess for a substantial distance, the locking recesses being adapted to receive vertical keys.
- 35 2. A building block having a main recess at one longitudinal corner for providing a vertical longitudinal extension, said block being provided at its ends with vertical locking recesses, said block being provided upon its horizontal face 40 remote from the main recess with a longitudinal vent groove, said block being provided in its vertical extension with an intermediate locking recess, said block having a vertical vent passage extending longitudinally of the block and projecting beyond one end of the intermediate locking recess for a substantial distance, the vertical vent passage being disposed upon one side of the intermediate locking recess.
- 45 3. A building block having a main recess at one longitudinal corner for providing a vertical longitudinal extension, said block being provided in its ends with vertical locking recesses extending through the top and bottom thereof, said block being provided upon its horizontal face 50 remote from the main recess with a longitudinal vent recess leading into the end locking recesses, said block being provided upon its horizontal face adjacent to the main recess with a longitudinal vent recess leading into the vertical end locking

5 recesses, the longitudinal vent recesses providing between them reduced hand-engaging portions, said block being provided in its vertical extension with an intermediate locking recess having its inner end closed, said block being also provided with a vertical vent opening extending longitudinally thereof beyond the end of the intermediate locking recess, the vertical vent opening 10 communicating with the longitudinal vent recesses.

4. A wall comprising horizontal layers of blocks, the blocks in one layer being arranged to break joint with the blocks in the next layer and the blocks in one layer being inverted with respect to the blocks in the next layer, each block 15 having a main recess in one longitudinal corner, each block having vertical locking recesses in its ends and an intermediate locking recess, each block having a vertical vent opening extending longitudinally beyond the end of the intermediate 20 locking recess for a substantial distance, and keys held within the locking recesses, the vertical vent openings extending beyond the sides of the keys to permit of ventilation.

5. A generally L-shaped building block having 25 vertical and horizontal portions forming a main longitudinal recess, the block being provided in its ends with vertical recesses, said vertical portion being provided with an intermediate vertical recess, the horizontal portion being provided with 30 upper and lower longitudinal ventilating grooves in communication with the end recesses.

6. An L-shaped building block comprising horizontal and vertical portions affording a main longitudinal recess, said block being provided in 35 its ends with vertical recesses, the vertical portion having an intermediate vertical recess, the horizontal portion having a pair of spaced vertical vent openings with a web between them, the web being arranged adjacent to the intermediate 40 vertical recess and the vertical vent openings extending longitudinally beyond the intermediate vertical recess.

7. An L-shaped building block comprising vertical and horizontal portions, said block being 45 provided in its ends with vertical recesses, the vertical portion being provided with an intermediate vertical recess, the horizontal portion being provided with upper and lower horizontal ventilating grooves leading into the end vertical recesses, the horizontal portion having a pair of 50 spaced vertical vent openings with a web between them, the web being arranged adjacent to the intermediate vertical recess and the vertical vent openings extending longitudinally beyond the vertical intermediate recess, the vertical vent 55 openings leading into the upper and lower horizontal ventilating grooves.

STANLEY BROZEK.
